UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

GUN-CARRIAGE TRAIL FOR ENABLING THE GUNS TO FIRE AT HIGH ANGLES OF ELEVATION.

1,335,462.

Specification of Letters Patent. Patented Mar. 30, 1920.

Application filed September 13, 1918. Serial No. 253,987.

To all whom it may concern:

Be it known that I, EUGÈNE SCHNEIDER, a citizen of the French Republic, and a resident of 42 Rue d'Anjou, Paris, France, have 5 invented a new and useful Improvement in or Relating to Gun-Carriage Trails for Enabling the Guns to Fire at High Angles of Elevation, which invention is fully set forth in the following specification.

10 This invention has for its object to provide an improved apparatus which will allow of converting rapidly and cheaply existing single-trail gun carriages having a relatively small vertical range of fire, in 15 such a manner as to provide a gun capable of being fired at low angles of elevation or at high angles of elevation at will. The improved apparatus is so designed that the conversion affects the smallest possible number 20 of parts, and more particularly does not change in any way the elevating mechanism of the gun.

According to this invention, the gun carriage trail is divided transversely into two 25 sections carrying respectively the anchoring device and the elevating mechanisms; a suitable apparatus being provided to allow of engaging the two sections with each other for firing in two positions, namely, one position 30 in which the two sections constitute prolongations of each other, and the second position wherein the front section incloses a certain angle with the rear section. In other words, when it is desired to fire at a higher 35 angle of elevation, the trail has its longitudinal axis broken by the front section being raised and engaged or fixed in the said raised position.

Two practical constructions of this invention 40 are illustrated in the accompanying drawings wherein:

Figures 1 and 2 illustrate a first modification of the invention, the trail sections being shown respectively in the position they 45 occupy for firing at low angles of elevation (Fig. 1) and for firing at high angles of elevation (Fig. 2).

Fig. 3 is a horizontal section on the line III—III of Fig. 1.

50 Fig. 4 is a partial section drawn to a larger scale, on the line IV—IV of Fig. 2.

Fig. 5 is a section of a detail drawn to a larger scale, on the line V—V of Fig. 3.

Fig. 6 is an elevation of a detail drawn to a larger scale, corresponding to Fig. 1, showing the jointing between the two trail sections. 55

Fig. 7 is a section on the line VII—VII of Fig. 6.

Figs. 8 to 11 show a second modification. 60

Fig. 8 is a partial elevation of the trail near the joint between the two sections, the latter being shown in position for firing at low angles of elevation.

Fig. 9 is a similar partial elevation, but 65 showing the trail sections in the position for firing at high angles of elevation.

Fig. 10 is a section on the line X—X of Fig. 8.

Fig. 11 is a partial section on the line 70 XI—XI of Fig. 10.

In these figures, A is the front section of a gun carriage trail; this section comprises in the usual manner bearings for the trunnions of the gun cradle C, and it carries the 75 elevating mechanism such as the pinion or pinions D of which the coöperating parts, such as the sector or sectors E, are carried by the cradle. B is the rear section of the trail; it carries the anchoring device. 80

The sections A and B are pivotally jointed to each other by an axle pin F that constitutes the pivot on which the front section A turns in its rising movement.

In the examples shown in Figs. 1 to 7, the 85 apparatus for engaging or fixing together the trail sections in position for firing at low angles of elevation or at high angles of elevation, is constituted as follows:

G is a part which is fixed by riveting or 90 other suitable means to the forward end of the rear trail section B. The lower portion of the said part comprises two bearings g for the pivot F; these bearings project to one and the other side of the cheeks of the 95 trail section B. g^1, g^2 are two half bearings formed on the upper edge of each of the cheeks G^1 of the part G, in an arc of a circle struck from the axis of the pivot F as a center. The angular distance α between 100 these two half bearings is equal to the angle through which the front section A is designed to be raised. H is an axle journaled at its middle in the front section A. I is a molded part fixed by riveting or other suitable means between the cheeks of the sec-

105

tion A; the axle H and the pivot F are journaled in the part I. The axle H is so arranged that its portions h can be engaged alternately in one or the other of the two pairs of half bearings g^1, g^2 . A hand crank H^1 for operating the axle H may be locked on the pivot F, for instance by means of a spring bolt h^1 mounted in the handle of the said crank.

10 In order to pass from the position for firing at low angles of elevation (Fig. 1), to the position for firing at high angles of elevation (Fig. 2), the spring-pressed pin h' is drawn out to release 15 the handle H' and the latter is turned through 180° . Axle H is thereby rotated to bring the crank portion h of the axle out of the half bearing g^1 and unlock the two trail sections A and B which, under the influence 20 of gravity, swing on their pivot connection F till the beveled end of section B butts against the beveled end of section A. When in this position the axle H is over the half bearing g^2 , having swung over the partition 25 g^3 separating bearings g^1 and g^2 . By turning axle H through another 180° by means of handle H' the locking portion h of axle H is moved into locking engagement with bearing g^2 and pin h' engages pivot F to 30 lock the handle thereto.

In order to prevent any rising movement in the case where the desired trench J for the recoil of the gun has not been previously dug in the ground, use may be made 35 of the safety apparatus shown in the drawings. An arm K is fixed at one end to the part I and is normally held between the sections A and B when these sections are arranged in prolongation of each other (Fig. 40 1). To prevent the overhanging of the arm K, its head K^1 may be fixed by means of two keys L inserted through the cheeks of the trail section B and having bayonet joint connection therewith as shown in detail in 45 Fig. 5. It is to be understood that if it has been forgotten to dig out the soil to the depth required for the recoil of the gun when firing at high angles of elevation, the butting of the head K^1 of the arm K will 50 prevent the rising of the front trail section A to the extent sufficient for causing its engagement in the position shown in Fig. 2.

It is to be understood that the arm K may serve as a lever for operating the section A in moving it from the position shown 55 in Fig. 2 into the position shown in Fig. 1.

In the construction shown in Figs. 8 to 60 11, the two trail sections A and B are pivoted to each other by means of a pivot F fixed in a fork-shaped part G attached to the front end of the rear section. A part I attached to the lower end of the trail section A is capable of pivoting by means of an eye on the said pivot F, this pivotal movement 65 being limited by a nib f formed on the said

pivot, being adapted to butt against the ends of a groove i formed in the part I.

The engagement of the trail sections A and B in the positions shown in Figs. 8 and 9 may be assured by the same mechanism 70 that serves to effect the raising of the section A. Upon a square portion of the pivot F there is fixed a toothed sector F¹ with which a worm I¹ engages that is journaled in a bracket I² fixed to the part I. The worm I¹ can be actuated by means of a hand crank I³.

Upon the rear trail section B there may be arranged a device such as the curved 80 guide M (Figs. 1, 2 and 4) for actuating during the raising of the front trail section A, any mechanism, such as for instance the mechanism controlling the variation of the length of the recoil, the position of which must vary with the high angles of elevation. 85

In the example shown in Figs. 1, 2 and 4, it is assumed that the guide M serves to actuate a lever N the pivotal movement of which produces a variation in the cross sectional areas for the passage of the liquid of 90 the usual hydraulic brake.

The lever N operates the known devices by rotating on its pivot n. It will be noted that in the raising movement of the trail section A, an anti-friction roller N¹ carried 95 by the lever N, strikes the curved guide M which forces the lever to rotate. By this means the operation of the known mechanism for varying the length of the recoil is automatically effected. 100

Whichever constructional form is adopted, it can be very easily adapted to a rapid and not expensive conversion of an existing gun which has been designed for firing only at low angles of elevation. It will be 105 merely necessary to cut the existing trail at the suitable desired point, and to affix on the respective inner ends of the trail sections, the cast steel parts G and I provided with the hereinbefore described devices for 110 connecting, engaging and safety purposes.

Having now described my invention what I claim as new and desire to secure by Letters Patent is:—

1. In a gun carriage, a gun trail comprising two sections having a hinge connection, one of said sections being provided with a plurality of half bearings arranged concentric with the hinge axis, and means on the companion trail section for engaging 115 said half bearings to lock the sections in different firing positions.

2. In a gun carriage, a gun trail comprising two sections having a hinge connection one member of said hinge having a plurality of half-bearings arranged concentrically with the axis of said hinge and the companion member of said hinge being provided with a crank-shaft bearing and a crank-shaft therein having a crank pin 120 125 130

adapted to engage said half bearings to lock the trail sections in different positions for firing.

3. In a gun carriage, a gun trail comprising two sections having a hinge connection, one member of said hinge having a plurality of half-bearings arranged concentrically with the axis of said hinge and the companion member of said hinge being provided with a crank-shaft bearing, a crank-shaft therein having a crank-pin adapted to

engage said half bearing, a crank handle for turning said shaft to bring said pin into locking engagement with said half-bearings, and means for locking said handle.

15

In testimony whereof I have signed this specification.

EUGÈNE SCHNEIDER.
